UNITED STATES PATENT OFFICE.

ANE P. SCHAT, OF THE HAGUE, NETHERLANDS.

MEANS FOR LAUNCHING LIFEBOATS.

Application filed February 3, 1921. Serial No. 442,032.

To all whom it may concern:

Be it known that I, ANE P. SCHAT, a citizen of the Netherlands, residing at The Hague, Netherlands, have invented certain new and useful Improvements in Means for Launching Lifeboats, of which the following is a specification.

My invention relates to improved means of launching lifeboats, and is in one or two points related to the construction set forth in my copending application, Ser. No. 441,618.

It has always been common practice in the art of suspending a lifeboat to lead the boat fall over a block (which may be the top block of a tackle) attached to the davit top at an invariable distance therefrom, for instance by means of an eye and a hook. In accordance with the present invention, however, said block is suspended from a rope or a cable running over the davit top, and attached either to the davit or to another member. In many cases, this suspension results in a reduction of the strains in the davit, thus avoiding a heavy construction.

A special advantage realized by the invention is the possibility of employing the tension in the cable from which the top block is suspended to force out the davit, or to apply a brake, or for any other suitable purpose. As a matter of course, the tension in this cable is practically equal to the full weight of the load, which is not the case with the hauling part of the boat fall rope through a tackle.

In order that the above may be fully understood, reference is had to the accompanying drawings showing some embodiments of my invention.

Fig. 1 is a side view of a davit having a boat suspended therefrom by a flexible member with its lower end secured to the stem of the davit.

Fig. 2 is a side elevation of a davit showing my improvement arranged to utilize the weight of the load to rotate the davit.

Fig. 3 is a top plan view of Fig. 2; and,

Fig. 4 is a side elevational view showing my improvement arranged to utilize the weight of the load to brake a drum on the deck of a ship.

Fig. 1 of the drawings illustrates in an

elevational view, an ordinary vertical rotary davit 1 serving for supporting a lifeboat 2 suspended from a tackle the top block 3 of which is attached to a rope 4. Said rope 4 is led over a sheave 5 pivoted to the davit top, thence over a guide roller 6 and finally to a cleat 7 on the davit, but it will be understood that said rope may also be attached to a cleat or the like on deck. The boat fall is designated by 8.

Figs. 2 and 3 are an elevation and a plan view respectively of a second embodiment of the invention. The boat fall here is wound on the drum of a winch 9, the rope 4 running from the guide roller 6 over a sheave 10 attached to the deck 11, and thence around a disc 12 keyed on the davit 1 concentrically therewith, in such a manner that the tension in said rope 4 tends to force the davit out. The rope 4 is secured to said disc 12 as at 12^a. It will be understood that the rope 4 may also be wound on disc 12 in the opposite direction so as to prevent the davit from rotating, which may be of value for rotary davits having their axes of rotation inclined towards the water.

Fig. 4 is an elevation of still another embodiment. As will be seen, the rope 4 runs from roller 6 over sheave 10 to one arm of a double-armed lever 13 pivoted to deck as at 14 and connected with the brake band 15 of the winch 9 which serves for hauling in and paying out the boat fall 8, the arrangement being such that the tension in rope 4 permanently tends to apply the brake of the winch.

A hand lever 16, which is pivotally connected with a rod 17 hinged to the other arm of lever 13 serves for releasing the brake-band 15, and, if necessary, for increasing the braking effect of said band.

Having now particularly described and ascertained the nature of my said invention, and in what manner the same is to be performed, I declare that what I claim is:—

1. In a device of the character described, the combination with a davit having a top block over which the boatfall is led, of an independent flexible member with said block suspended therefrom; and mechanism indirectly associated with the davit, to which mechanism said flexible member is secured,

said mechanism being adapted to be operated by the tension in the flexible member, whereby the tensional force applied to said mechanism is proportionate to the weight 5 of the suspended load.

2. In a device of the character described, the combination with a davit having a top block over which the boatfall is led, of a flexible member for suspending said block 10 at a variable distance from the davit top proportionate to the weight of the suspended load; and operative mechanism adjacent the davit; said flexible member being connected therewith, whereby the tension of 15 said member is utilized to operate said mechanism.

3. In a device of the character described, a davit adapted to rotate on its longitudinal axis from inboard to outboard position 20 to put a lifeboat overboard, said davit having a top block over which the boatfall is led; and a flexible member for suspending said block at a variable distance from the davit top; mechanism on deck adapted to 25 be operated by a pull thereupon, said flexible member being led from said block over the davit top to said mechanism on deck to form an operative connection between the same and said suspended block, whereby to 30 utilize the pull of the block upon said flexible member to operate said mechanism.

4. In a device of the character described, the combination with a davit having a top block over which the boatfall is led, of a 35 flexible member for suspending said block at a variable distance from the davit top; a drum around which the hauling end of the boatfall is wound; and braking mechanism for said drum, with the lower end of said 40 flexible member operatively connected with said braking mechanism, whereby the drum is braked in proportion to the weight of the suspended load.

5. In a device of the character described, 45 the combination with a davit having a top block over which the boatfall is led, of a flexible member for suspending said block at a variable distance from the davit top; a drum around which the hauling end of the 50 boatfall is wound; braking mechanism for said drum, with the lower end of said flexible member operatively connected with said braking mechanism, whereby to brake the drum in proportion to the weight of the suspended load; and independent means 55 operatively connected with the braking mechanism for regulating the action thereof.

6. In a device of the character described, 60 the combination with a davit having a top block over which the boatfall is led, of a flexible member for suspending said block at a variable distance from the davit top; a drum around which the hauling end of the boatfall is wound; braking mechanism 65 for said drum, with the lower end of said

flexible member operatively connected with said braking mechanism, whereby to brake the drum in proportion to the weight of the suspended load; and additional means operatively connected with said braking 70 mechanism for manually controlling the same.

7. In a device of the character described, the combination with a davit having a top block over which the boatfall is led, of a 75 flexible member for suspending said block at a variable distance from the davit top; a drum around which the hauling end of the boatfall is wound; braking mechanism for said drum, with the lower end of said 80 flexible member operatively connected with said braking mechanism, whereby to brake the drum in proportion to the weight of the suspended load; and adjustable means also 85 operatively connected with said braking mechanism for adjustably controlling the same.

8. In a device of the character described, the combination with a davit having a top block over which the boatfall is led, of a 90 flexible member for suspending said block at a variable distance from the davit top; a drum around which the hauling end of the boatfall is wound; braking mechanism for said drum, with the lower end of said flexible member operatively connected with said 95 braking mechanism, whereby to brake the drum in proportion to the weight of the suspended load; and manually controlled auxiliary braking mechanism connected 100 with said first named braking mechanism for cooperating with the load to control the braking mechanism.

9. The combination with a davit and mechanism not directly associated therewith, of a flexible load-supporting member, 105 said mechanism having a movable part by which it is operated, the flexible member being connected at one end to said movable part and extending from the same over the davit top and depending therefrom, with means at said depending end for engagement with the load to be supported by the davit, whereby the depending load moves said flexible member longitudinally and thereby operates said mechanism.

10. In a device of the character described, the combination with a davit having a top block over which the boatfall is led, of an 110 independent flexible member for suspending said block from the davit top; a drum around which the hauling end of the boatfall is wound; braking mechanism for said 115 drum with the lower end of the flexible member operatively connected therewith, whereby to brake the drum in proportion to the weight of the suspended load; and additional means operatively connected 120 with said braking mechanism for manually controlling the same, said last named means 125 130

being arranged to permit the free movement of the braking mechanism in a direction to apply the brakes.

11. In a device of the character described, 5 the combination with a davit having a top block over which the boatfall is led, of an independent flexible member for suspending said block from the davit top; a drum around which the hauling end of the boat- 10 fall is wound; braking mechanism for said drum, with the lower end of the flexible member operatively connected therewith, whereby to brake the drum in proportion to the weight of the suspended load, and to

utilize approximately the entire weight of 15 the load in effecting said braking operation; and additional means operatively connected with said braking mechanism for manually controlling the same, said last named means being arranged to permit the free movement 20 of the braking mechanism in a direction to apply the brakes, and also arranged to automatically lock said braking mechanism against a releasing movement as the brakes are progressively applied by the load. 25

In testimony whereof I affix my signature.

ANE P. SCHAT.
